UNITED STATES PATENT OFFICE.

RAYMOND H. McMINN, OF CHICAGO, ILLINOIS.

COIN-CONTROLLED CLOCK.

Application filed April 20, 1921. Serial No. 462,836.

To all whom it may concern:

Be it known that I, RAYMOND H. McMINN, a citizen of the United States, residing at Chicago, in the county of Cook and State of Illinois, have invented certain new and useful Improvements in a Coin-Controlled Clock, of which the following is a description.

My invention relates to improvements in 10 clocks, and more particularly to a combined clock and bank, and in which it is necessary that a coin be inserted before the clock can be wound. One of the objects of my invention is to provide a coin-controlled winding mechanism for a clock as above described, in which the coin will be caused to drop into a suitable coin receptacle by the action of the clock itself, so that the same coin cannot be used for successive windings. 15 The invention has among its further objects the provision of a device of the kind described which is simple, convenient, compact, durable, reliable, efficient and satisfactory for use wherever found applicable. 20 Many other objects and advantages of the construction herein shown and described will be obvious to those skilled in the art from the disclosures herein given.

To this end my invention consists in the 25 novel construction, arrangement and combination of parts herein shown and described, and more particularly pointed out in the claims.

In the drawings, wherein like reference 30 characters indicate like or corresponding parts,

Fig. 1 is a top plan view of my device;

Fig. 2 is a rear elevation of the same;

Fig. 3 is a section taken substantially on 40 the line 3-3 of Fig. 2;

Fig. 4 is a section taken substantially on the line 4-4 of Fig. 1;

Fig. 5 is a fragmentary sectional detail of the automatic coin-ejecting means;

Fig. 6 is a rear elevation of a modified 45 form of my device; and

Fig. 7 is a side elevation of the same.

In the drawings, wherein I have shown the preferred embodiment of my invention, 50 1 represents the outer casing of a clock, and 2 the rear wall or the bell portion thereof. The clock may be of any desired or preferred construction having the usual hand-setting device and alarm-winding means, 55 and a winding stem 3, whereby the clock may be wound for use. Secured to the outer

end of the winding stem 3 is a hollow cylindrical stem extension member having an end wall 4, at which it is secured to the stem 3 by a screw 5 or the like, the cylindrical wall of the stem extension member being slotted or cut away to provide a pair of arcuate leg or wall members 6 separated by the spaces or slots 7 therebetween, said slots extending substantially the full length of 60 the stem extension member. Concentric with the stem extension member is a stationary annular ring chamber or guide member 8 having a plurality of circumferentially spaced and radially extending slots 70 9 and 10 through its arcuate wall, said slots being of a width to receive a suitable coin therethrough.

Between the annulus 8 and the cylindrical stem extension member 4 is concentrically 75 positioned a hollow cylindrical winding key 11, said winding key being freely rotatable between and bearing on both of said members, and having a diametral slot 12 therethrough of a thickness substantially equal to 80 that of slots 9 and 10. The end wall 13 of the member 11 is preferably positioned over the outer open end of the stem extension member 4, and at the outer end of said end wall is secured a thumb nut 14 85 or the like, whereby the winding key may be gripped for manual turning. The peripheral edge of the end wall 13 is preferably shouldered or cut away so as to provide an annular end abutment 15 adapted 90 to engage with one wall of a stationary casing or closure and prevent axial movement of the winding key. It will be understood that the parts 6 and 11 may fit one within the other as shown, or vice versa, the 95 essential feature being that they shall have registering slots therethrough, whereby the coin may be held therein to turn the stem.

In the circumferential wall of the member 8 at its bottom, is a radial slot 16 of a size substantially greater than that of the slots 9 and 10, and adapted to form an exit for the coin into the coin receptacle S. The coin receptacle S comprises a cover or casing having an inner wall 17 and 100 a laterally extending flange or wall 18 projecting outwardly therefrom, said casing being preferably hollow and enclosing said stem and winding means. Screws 19 or the like may be used for securing the casing S 105 to the rear wall of the clock, and if desired, a washer or other suitable spacing means 110

20' may be interposed between the adjacent walls of the clock and the coin receptacle so that the sound of the alarm bell 2 will not be interfered with. The laterally projecting 5 wall of the coin receptacle has an arcuate portion 21 corresponding to the circular contour of the clock and has a radial portion 20 adjoined thereto, and portion 22 between said arcuate portion and the radial portion, 10 and of any preferred outline to suitably enclose the projecting mechanism. If desired the coin receptacle may be detachable so that it may be removed when full and replaced. In alignment with said slotted openings 15 9 and 10, the casing is provided with coin-receiving slots 23 and 24, each comprising a pair of parallel spaced radially extending tongues or walls 25, 26, one or both of said walls being made flexible by bending its free 20 end backwardly upon itself, and preferably inwardly of the slot, so that the width of the slot opening is slightly less than the width of the coin to be received, and thus when a coin is inserted, the tongues will yieldingly hold it in place and tend to present its retraction. A part 27 secured at one end to the member 8 and having its free end adjacent the opening 16, is adapted to assist in preventing the coin being shaken back into 25 the slot. If desired, a spring-pressed finger 37, movable radially and having a radially extending end adapted to yieldably bear on the periphery of the key 11 so as to releasably engage in either of the diametrically 30 arranged cam-ways 38 in the periphery of the key 11, may be arranged. As shown in Fig. 5, as the key turns freely, due to the 35 unwinding action of the spring, the cam-way 38 is yieldably engaged by the finger 37, said finger snapping thereinto and jerking the key into position (in dotted lines), so that its slots 12 will register with the slot 16, relieving the coin from the turning pressure and cause the coin to be ejected there- 40 through.

The operation of the device is as follows: With the clock face down, a coin C is inserted through either of the slots 9 or 10, depending upon the position of the winding 50 key at the time, and the key 11 then turned until its diametral slot 12 registers with the slot 9 or 10, as the case may be, whereby the coin will drop through the slot 9 or 10 and be positioned in the winding key within the 55 inner peripheral surface of the member 8; then when the key is turned, the coin will abut against and engage with the longitudinal arcuate posts 6 and transmit the torque of the key to the stem. After the stem has 60 been wound, it is not necessary that the key be turned so that the coin will be in registry with the slot 16 so as to fall therethrough onto the guide 27 and into the receptacle, and as a matter of fact, it might be impossible to so turn the same until the spring un- 65

wound. The running of the clock has a tendency to turn the stem and key in the direction of the unwinding of the spring of the clock, and as the key so turns and the cam-way 38 is engaged by the spring-pressed finger 37, said finger will snap into said cam and push or accelerate said key a slight distance ahead of the arcuate turning of the interlocked coin and stem so that the slots 12 are in registry with the slot 16, and therefore the coin lagging behind, will have the pressure therein released and be caused to drop through said slot 16 and into the receptacle. Any desired number of posts 28 may be positioned at suitable points in the casing, 70 each having a threaded bore 29 therein, adapted to receive the attaching screws 30 for holding a cover plate 31 in place on said casing. If desired, a few screws 32 of smaller size than the screws 30 may extend through 75 the cover plate and be secured to the cylindrical guide member 8.

In order that the coins in said receptacle may be extracted whenever a sufficient amount have accumulated therein, I have 80 provided a lock-controlled door 33 having a lock 34 thereon, the latch bolt 35 of said lock adapted to be engaged in a slot 36 in one of the walls of said coin receptacle. The 85 location and number of the coin slots in which the coin may be inserted may be varied at will without changing the operation of the device.

In Figs. 6 ad 7, I have shown a modified 90 form of device in which the coin receptacle 50 is at the bottom of the clock instead of on the rear wall thereof. In this modification a coin guide or chute 52 is provided, leading downwardly from the coin-controlled winding key to the bottom of the receptacle. I have also shown a lock-controlled door 51 in said receptacle.

Having thus described my invention, it is 95 obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In combination, a clock, a winding 100 stem therefor, a coin-controlled key for operating said winding stem, and means for automatically accelerating said key relative to the unwinding movement of said stem to release a coin therefrom.

2. In combination, a clock, a winding 105 stem therefor, a coin-controlled key for operating said winding stem, and means set in operation by the winding mechanism of the clock for automatically accelerating the unwinding movement of said key relative to 110

the unwinding movement of said stem to release the coin therefrom.

3. In combination, a clock, a winding stem therefor, a coin-controlled key for operating said winding stem, said stem and key being adapted to receive a coin to operatively connect them, and means for automatically accelerating the unwinding rotation of said key relative to said stem to release said coin therefrom.

4. In combination, a clock, a winding stem therefor, a coin-controlled key for operating said winding stem, said stem and key being adapted to receive a coin to operatively connect them, and means set in operation by the winding mechanism of the clock for automatically accelerating the unwinding of said key relative to said stem to release the coin held therebetween.

5. In combination, a clock, a slotted winding stem therefor, a slotted key for said stem, said key and stem being adapted to receive a coin through said slots to operatively connect said stem and key, and automatic means set in operation by the unwinding of said stem for releasing said coin after said key has been rotated through one or more revolutions.

6. In combination, a clock, a winding stem therefor, a winding key on said stem, a slotted coin receptacle over said stem, said key being normally freely rotatable on said stem, and means on said stem and key engageable by a coin insertable into the slot in said receptacle for preventing said independent rotational movement of the key on the stem, thereby permitting the stem to be wound through one or more revolutions, and means for automatically accelerating the unwinding of the key relatively to said means on the stem to permit the coin to fall into the receptacle.

7. In combination, a clock, a winding stem therefor continuously driven in one direction, a radially slotted cylindrical member affixed to and projecting from said stem, a cylindrical key on said cylindrical member and having a radial slot therethrough, a cy-

lindrical guide chamber enclosing the cylindrical wall of said key and preventing lateral movement thereof, said guide chamber having a plurality of circumferentially spaced radial slots therethrough, whereby a coin may be inserted through the one of said circumferentially spaced slots which is in alignment with the aligned slots of the stem and key and lie athwart the slotted walls of said stem and key, permitting said stem to be wound, said guide chamber having a radial discharge slot through its peripheral wall, means for automatically accelerating the unwinding of the key relative to said means on the stem, whereby the coin will be released by the unwinding movement of the stem into a suitable receptacle after the winding operation.

8. In combination, a clock, a winding stem therefor, a key having a slot therethrough to receive a coin through said slot to operatively connect said stem and key together, and means automatically set in operation by the unwinding movement of said stem to release said coin.

9. In combination, a clock, a winding stem, a winding key surrounding said stem, both said stem and said key having aligned slots laterally therethrough, a coin receptacle having a part fitting over said stem and having a slot communicating with the slot in the stem, whereby a coin inserted through the slot in the receptacle will be tightly held in the registering slots of the stem and winding key athwart the slotted walls thereof upon winding, and prevent independent rotational movement therebetween, and means automatically operable to relieve the pressure on the coin to cause it to drop into said receptacle.

In testimony whereof, I have hereunto signed my name in the presence of two subscribing witnesses.

RAYMOND H. McMINN.
